Frederick Breitenfeld
His ATTORNEY

UNITED STATES PATENT OFFICE

FRANK SCHWARTZ, OF NEW YORK, N. Y.

MICROMETRIC DRAWING INSTRUMENT

Application filed February 11, 1927. Serial No. 167,383.

My present invention relates generally to drawing instruments, and has particular reference to a micrometric device for employment either as an attachment for existing instruments or as a constituent part of beam compasses and the like.

One object of the invention is to provide a device which may be employed as an attachment for compasses or similar instruments, whereby micrometric adjustment is rendered possible.

In the employment of ordinary compasses, dividers, or similar instruments, it frequently happens that the user is desirous of repeatedly employing the same adjustment. Compasses, other than bow compasses, unless specially constructed and hence relatively expensive, are usually incapable of being locked in any particular setting; accordingly, where a particular setting is to be retained for a considerable period, or to be repeated from time to time, much annoyance and inaccuracy occurs and much time is wasted in effecting this purpose.

It is another object of the present invention to provide an attachment which will obviate these disadvantages and will permit an ordinary compass or similar instrument to be rendered equally as accurate and convenient as the bow compass type.

Briefly, my invention contemplates the provision of a rigid beam so constructed as to be applicable transversely of the spread legs of a compass, the beam being provided with means adjustable with respect thereto for engaging the spread legs and thereby forming a triangular structure in association therewith.

Furthermore, my invention contemplates the provision of at least one slidable element upon the beam, and the arrangement of means operatively interposed between said element and the beam for rendering minute adjustment of the element, longitudinally of the beam, possible.

It is a feature of my invention to provide my device in a form which is so simple of construction as to render the manufacture thereof extremely inexpensive. More particularly, I contemplate employing such simple elements as wire rods and constituent parts

constructable by stamping, bending, or similar operations, from integral flat blanks of material.

Other features of my invention lie in the particular structural natures and characteristics of the various elements and portions, by virtue of which a complete yet inexpensive structure results.

For the attainment of the foregoing objects and such other objects of my invention as may hereinafter appear or be pointed out, I have illustrated several embodiments of my invention wherein:

Fig. 1 is a front elevational view of an ordinary compass having an attachment associated therewith and employing the features of my invention;

Fig. 2 is a view of the essential portion of Fig. 1, taken from the rear;

Fig. 3 is an exploded view of the elements 70 in the left-hand assembly of Fig. 1;

Fig. 4 is a similar exploded view of the elements in the right-hand assembly of Fig. 1;

Fig. 5 is a view similar to Fig. 1, showing a 75 modification;

Fig. 6 is a fragmentary perspective view of the end of the wire beam of Fig. 5;

Fig. 7 is a perspective view of the modified sliding element shown in Fig. 5; and 80

Fig. 8 is a perspective view of a modification of the slidable element employed in Fig. 1.

Referring to the drawings and particularly to Figs. 1-4, it will be observed that I have shown an ordinary compass 20 having pivoted legs 21 and 22. Associated with the compass is an attachment embodying the features of my invention and comprising a beam 23 extending transversely across the spread legs 21 and 22 and forming a triangular structure in association therewith.

In the form shown in Fig. 1, the beam 23 is constituted of an ordinary strip of stiff wire, and the end thereof is bent, as shown more clearly in Fig. 4, to provide an offset end portion 24 having an opening 25 therein, the axis of the opening 25 lying along a line parallel to the axis of the beam.

Slidably mounted upon the beam 23 are two 100

elements 26 and 27, each being provided with means for frictionally engaging one of the legs 21 and 22. Referring more particularly to Fig. 3, the structural nature of the assembly of which the element 26 forms a part will be more clearly understood.

The element 26 has a body portion with an opening 27' therein, one end of the body portion being bent to form a flange 28 adjacent to the opening 27' and the other end being bent to form a channel 29 adapted to accommodate the rod or beam 23 therein. The element 26 is preferably associated with a disc 30 having an opening 31, a bolt 32 being designed to pass through the openings 31 and 27' and to be engaged by a nut 33. The nut 33 is preferably a square nut and is adapted to have one edge abut against the flange 28 so as to prevent rotation thereof when the bolt 32 is turned. In this way, the beam 23 is securely clamped between the channel 29 and the disc 30, after the desired adjustment has been effected.

Adapted to cooperate with the opposite surface of the disc 30 is a clamp 34 having an opening 35 to receive the bolt 32, and having a channeled end 36 adapted to frictionally embrace the leg 21. It will be noted that the clamp 34 is pivotally supported, thereby permitting the mutual association of the beam and the leg 21 in firm engagement regardless of the inclination of the leg 21.

In use, the leg 21 is first associated with the assembly illustrated in Fig. 3, and thereafter the other leg 22 is similarly associated with the second slidable element.

Referring now to Fig. 4, it will be seen that the element 27 is provided with an opening 37 adjacent to which a small flange 38 is provided having a similar function to the flange 28 with respect to a corresponding nut 39. The upper edge of the element 27 is rolled or bent to provide two sleeves or channels 40 in which the beam 23 is designed to accommodate itself. Cooperable with the opposite face of the element 27 is a clamp 41 substantially equivalent to the clamp 34 and having a similar channelled end 42 for the accommodation of the leg 22. A bolt 43 is designed to pass through the clamp 41 and the element 27 and to be engaged by the nut 39.

The structure so far described is usable by itself for the purpose of locking or setting a compass of the character illustrated in a fixed desired position. To effect a change in the setting it is not necessary to remove the device entirely, since a simple loosening of the one or both of the bolts 32 and 43 is sufficient to permit pivoting of the clamps 34 and 41 so that the angular relationship of the legs 21 and 22 may be changed.

To permit the effecting of a further and more minute adjustment, I provide a portion 44 upon the element 27 in a position longitudinally aligned with the opening 25 in

the offset end 24. Between the offset end 24 and the portion 44 I arrange micrometric means for minutely adjusting the element 27 longitudinally of the beam 23. I have illustratively shown a threaded rod 45 carried by the portion 44 and extending through the opening 25, a knurled nut 46 engaging with the rod 45 on the opposite side of the end 24, and a coil spring 47 being wound about the rod and extending between the portion 44 and the end 24.

The spring 47 will normally tend to force the element 27 to the left (in Fig. 1). Hence, it will be readily understood that by loosening the nut 46, a slight motion to the left will be effected, whereas tightening of the nut 46 will draw the element 27 toward the right. This movement of the element 27 is extremely slight and in the nature of a micrometric adjustment. During such movement, the angularity of the leg 22 will shift to a very slight degree, and this shifting will be permitted by the nature of the frictional engagement between the leg 22 and the element 27.

Referring for the moment to Fig. 8, a modified form of element, corresponding to the element 27, is illustrated wherein the rolled portions 40 are eliminated. Whereas the portion 44 was constituted in Fig. 1 of an integral tab formed by bending up an end portion of the element, in Fig. 8, this tab has been extended to the top edge of the element, thereby permitting the provision of an opening 48. A corresponding tab is provided on the opposite end of the element and an opening 49 is provided in alignment with the opening 48, the beam 23 being adapted to pass through these openings. Furthermore, an opening 50, corresponding to the opening 37, has been provided in closer relationship with respect to the tab 51, the latter serving thus to fulfill the function previously filled by the flange 38.

In Figs. 5-7, I have illustrated a modified form wherein the rod 23 has been replaced by a double rod 52 formed by bending a wire element upon itself. The offset end 24 is herein provided by the medial portion of the wire element, and this portion is bent as shown in Fig. 6 to provide an opening 53 corresponding to the opening 25 of Fig. 4.

In this form, the elements 26 and 27 are modified to provide accommodations for both rods 52. In Fig. 7, I have shown a flat element rolled along its opposite edges to provide sleeves 54, these sleeves themselves serving to retain a square nut 55 in correct position and thereby obviating the necessity for providing a flange 38 or similar arrangement.

It will be obvious that many changes in the details herein described and illustrated for the purpose of explaining the nature of my invention may be made by those skilled in the art without departing from the spirit and scope of the invention as expressed in the ap-

pendent claims. Such a construction would permit the beam to be made of steel and to be considerably thinner. In the embodiment illustrated, the beam is designed to be of aluminum or similar material. Furthermore, a leaf spring might be interposed between one of the flanges 67 and the beam to enhance the stability of its movement. In the embodiment shown, such a spring would be split longitudinally to provide one portion bearing upon the beam 56 and another portion bearing upon the auxiliary beam 57.

Moreover, the sliding elements exemplified by the elements 63, 27, etc., might be constructed in a variety of ways without departing from the spirit of the invention. It is therefore intended that these details be interpreted as illustrative and not in a limiting sense.

Having thus described my invention and illustrated its use, what I claim as new and desire to secure by Letters Patent is—

1. A device of the character described comprising a beam, an element slidably mounted thereon and provided with means for engaging a leg of a drawing instrument, said means being independent of said leg and adapted to engage the latter at any point thereof, and micrometric means operatively interposed between the beam and said element for minutely adjusting the element and leg longitudinally along the beam.

2. A device of the character described comprising a beam having an offset end portion, an element slidably mounted on the beam and provided with means for engaging a leg of a drawing instrument, said means being independent of said leg and adapted to engage the latter at any point thereof, said element having a portion longitudinally aligned with said end portion, and micrometric means operatively interposed between said aligned portions for minutely adjusting the element and leg longitudinally along the beam.

3. As an attachment for a two-legged drawing instrument, a micrometric adjusting device comprising a rigid beam for transverse disposition across the spread legs of the instrument so as to form a triangular structure therewith, means adjustable along the beam for attaching said legs to desired spaced portions of the beam, said means being independent of said legs and adapted to engage the latter at any point thereof, said means including an element slidably associated with the beam, and means operatively interposed between the beam and said element for minutely adjusting the latter and attached leg with respect to the beam.

4. As an attachment for a drawing instrument having pivoted unperforated legs, a micrometric adjusting device comprising a rigid beam for transverse disposition across said legs, means adjustable along the beam for attaching said legs to desired spaced por-

tions of the beam, said means including an element slidably encircling said beam and a pivotally adjustable clamp carried by said element and adapted to enclose and frictionally engage one of said legs, and means operatively interposed between the beam and said element for minutely adjusting the latter with respect to the beam.

5. As an attachment for a drawing instrument having pivotally adjustable legs adapted to be spread relative to each other, a micrometric device comprising a wire beam for transverse application across said legs, said beam being provided with an end portion having an open therein whose axis is spaced from the beam and parallel thereto, means adjustable along the beam for frictionally engaging said legs in desired spread disposition, said means including an element slidably associated with the beam and having a portion aligned with said axis, and means extending through said opening and associated with said aligned portion for minutely adjusting the element with respect to the beam.

In witness whereof, I have signed and sealed this specification this 7th day of February, 1927.

FRANK SCHWARTZ.
